UNITED STATES PATENT OFFICE.

BENJAMIN F. STEPHENS, OF REEVES, TEXAS.

RAIL-JOINT.

SPECIFICATION forming part of Letters Patent No. 693,919, dated February 25, 1902.

Application filed June 28, 1901. Serial No. 66,411. (No model.)

To all whom it may concern:

Be it known that I, BENJAMIN F. STEPHENS, a citizen of the United States, residing at Reeves, in the county of Briscoe and State of Texas, have invented certain new and useful Improvements in Rail-Joints; and I do hereby declare the following to be a full, clear, and exact description of the invention, such as will enable others skilled in the art to which it appertains to make and use the same.

The purpose of this invention is to provide a self-locking rail-joint of novel construction and which will preclude the use of bolts or analogous fastenings, the weight of the rails and their securement to the ties being sufficient to hold the parts of the clamp close against opposite sides of the rail ends.

The clamp consists of parts having interlocking connections, which are brought together or separated by relatively sliding the parts according as they are to be coupled or uncoupled, the parts being of similar formation, rights and lefts, and each comprising a base portion and a side portion, the base portions having the interlocking means.

For a full description of the invention and the merits thereof and also to acquire a knowledge of the details of construction of the means for effecting the result reference is to be had to the following description and drawings hereto attached.

While the essential and characteristic features of the invention are susceptible of modification, still the preferred embodiment of the invention is illustrated in the accompanying drawings, in which—

Figure 1 is a perspective view of a rail-joint embodying the invention, parts being broken away. Fig. 2 is a perspective view of the clamp inverted. Fig. 3 is a section of the clamp, showing the relation of the parts either when first placed together or about to be separated. Fig. 4 is a view similar to Fig. 3, showing the relation of the parts when coupled. Figs. 5 and 6 are detail perspective views showing more clearly the formation of the interlocking means.

Corresponding and like parts are referred to in the following description and indicated in all the views of the drawings by the same reference characters.

The clamp comprises the members 1 and 2 of similar formation, being rights and lefts, so as to fit opposite sides of the rails when forming the joint. Each member consists of a base portion and a side portion, the base portion coming beneath the foot of the rails and the side portion being adapted to lie against the sides of the rails and come beneath the head thereof. The member 1 has a series of slots or openings in its base portion 3, said openings being wide at one end, as shown at 4, and contracted or narrowed at the opposite end, as shown at 5. The edge of the openings adjacent the outer edge of the base 3 is straight, whereas the opposite edge is broken or offset conformable to the wide and narrow portions of the openings. The inner edge of the narrow part of the opening is turned upward adjacent the wide part of the opening, as shown at 6, for the purpose presently to be described.

The member 2 is provided along the edge of its base portion 7 with a series of offstanding projections, either formed with the member or secured thereto in any substantial way. These projections consist severally of a shank 8, hook 9, and offstanding lip 10, the top side of the lip 10 being a distance below the bottom side of the shank 8 corresponding to the thickness of the base 3, thereby admitting of the shank 8 overlying the base 3 and the lip 10 underlapping said base when the parts of the clamp are assembled.

The members of the clamp may be cast, pressed, or otherwise formed and are sufficiently stout to withstand the strain to which the clamp will be subjected in practice. The members of the clamp when brought together have the hooks 9 inserted in the wide or enlarged portions 4 of the openings of the base 3, the upper ends of the side members being separated. After the hooks 9 have been engaged with the wide portions of the base 3 the upper ends of the clamp members are brought together and against opposite sides of the rails 11, which are placed between the members of the clamp prior to bringing the upper ends of the side members together. After the upper ends of the clamp members have been brought together the members 1 and 2 are moved longitudinally and so as to

cause the hooks 9 to pass from the wide ends 4 of the opening into the narrow ends, and this movement causes the lips 10 to pass beneath the parts 6, bordering upon the inner 5 sides of the narrow parts 5 of the opening. By having the corners or ends upwardly bent, as shown at 6, the lips 10 are enabled to pass readily beneath the parts of the base 3, bordering upon the narrow portions of the opening 10 therein. As the lips 10 pass by the part 6 the upper ends of the clamp members are forced together and securely grip opposite sides of the rails. The clamp is located so as to extend about an equal distance upon 15 opposite sides of the joint formed between proximal ends of adjacent rails. After the clamp has been properly positioned it is secured to the ties by spikes, and, if desired, the joint may be made more secure by bolting 20 the upper ends of the clamps through the web of the rail in the usual way, although this is not necessary. To prevent slipping of the clamp when in position, the vertical portion of its members is provided with inner 25 projections 12 to enter openings or corresponding depressions in the webs at the end portions of the rails. These projections 12 may be pressed from the clamp members or provided in any desired way.

30 Having thus described the invention, what is claimed as new is—

1. In a rail-joint, a clamp composed of complementary parts, each consisting of a base and a side portion, the base of one of the 35 parts having openings comprising a wide and a narrow portion, and projections applied to the opposite part and comprising hooks and offstanding lips, the said lips being adapted

to underlap the base provided with the openings, substantially as set forth. 40

2. In a rail-joint, a clamp composed of corresponding parts each comprising a base and a side portion, the base of one of the parts having openings comprising a wide portion and a narrow portion, the inner edge portion 45 of the base bordering upon the narrow part of the opening being upturned, and projections applied to the base portion of the other part and comprising a shank, a hook and an offstanding lip, the latter being adapted to 50 underlap the upturned portion of the base bordering upon the narrow part of the opening, substantially as and for the purpose set forth.

3. In a rail-joint, a clamp constructed substantially as set forth, the same comprising similarly-formed members, rights and lefts, each member consisting of a base and a side portion, the base of one of the members having a series of openings formed of a wide and 60 a narrow portion and having the inner edge of the narrow part of the opening upturned, and hooked-shaped projections applied to the base portion of the opposite member and formed with offstanding lips which are adapted to underlap the inner edge portion of the base bordering upon the narrow part of the opening, the interlocking of the members being effected by a relatively sliding movement, 65 substantially as set forth. 70

In testimony whereof I affix my signature in presence of two witnesses.

BENJAMIN F. STEPHENS. [L. S.]
